JACKET CROWN, MODEL, AND METHOD OF APPLYING

Application filed March 23, 1928. Serial No. 264,212.

My invention relates to the art of dentistry where an injured tooth is to be restored to good appearance and function by means of a hollow porcelain tooth form, commonly known as a porcelain jacket crown and the object of my invention is:

To provide a procedure with appliances whereby much time now consumed can be saved in thus restoring teeth,

10 To provide means whereby much of the exacting skill now required to make such a restoration, may be dispensed with and at the same time more satisfactory results be more surely attained.

15 I attain these objects in the following manner and by the structure illustrated in the accompanying drawing in which:

Fig. 1 is a natural tooth badly decayed and calling for a porcelain jacket crown.

20 Fig. 2 is the same tooth trimmed down ready to receive such a crown.

Fig. 3 is a porcelain jacket crown.

25 Fig. 4 is the crown in place on tooth but not trimmed to match the neck surface-circumference.

Fig. 5 shows the same after it has been trimmed to match.

30 Fig. 6 is a section of a porcelain crown, front view.

Fig. 7 is a sectional side view of same.

Fig. 8 is a socket-former, with a projection B of the size and shape of a prepared natural tooth, the ridge W, the gateway H and the removable handle K, all showing.

35 Fig. 9 shows a gate for the gateway H in socket-former of Fig. 8.

Fig. 10 is an end view of socket-former.

Fig. 11 is a molding ring showing slots P. P. P. P.

40 Fig. 12 is an end view of same ring showing the separating strips R in slots and side view of strip R.

Fig. 13 is a sectional view of a molding ring T into which is placed the socket-former with tooth-model B. Gate I is in place and a crown M is on model B. Separating strip R in slot and the balance of hole in ring filled with investment N.

45 Fig. 14 is a section of same ring T with the investment N re-assembled in place.

Fig. 15 shows the same as 14, but with low fusing metal S in mold where porcelain crown was.

Fig. 16 is a sectional view of same ring T and investment N with fusible metal S into 55 which has been pressed socket-former B causing the fused metal to flow out thru gateway as Ss.

Like letters refer to the same parts throughout the several views.

60 Porcelain jacket crowns are first made up in stock of various sizes, forms and shades to meet all requirements.

For a given case, a crown is selected to 65 match the natural teeth. This is then placed over the socket-former made for it, (each size of socket having a socket-former to conform to itself) all of which is then placed in the large end of molding ring.

70 Separating strips are placed in slots and the remainder of the ring is filled with investment made of some material like plaster of Paris that will flow and then set to form a mold, all as shown in Fig. 13.

75 When the investment is set, all is pushed out of the large end of ring and the separating strips are withdrawn. The investment is then split away from crown and re-assembled in molding ring as shown in Fig. 14, 80 T being the ring, N the investment.

85 Into this is poured some low-fusing metal as S in Fig. 15 and into this fused metal is pressed, after it has been heated, the socket-former B causing the excess metal to flow away thru the gateway H which has been made by removing gate I. This excess metal is shown as Ss. Thus we have a metal model of the porcelain crown to guide us in cutting down the tooth end to fit the porcelain crown.

90 But to give additional help, we have socket-formers of larger sized B parts, to make semi-duplicates of the crown; that in being larger will go over the tooth end before the tooth end is so near of a size to fit the porcelain crown. These can be of one or more sizes 95 larger than the exact duplicate and be used at the beginning of the tooth trimming using the largest one first, then the next smaller.

99 So having these crowns of metal, we now proceed to prepare the tooth end. First cut-

ting away only part of as much as we can see will be necessary, or just enough to receive the metal crown model with the largest socket. By pressing this as far on as possible 5 it will rub off where it is tight and leave a mark on the tooth where the tooth needs to be trimmed more. When these high points are trimmed away, the metal crown is again tried on and in such manner the tooth is 10 worked down until a loose fit is obtained of this largest metal crown. Then the next smaller metal crown is used the same way to still further reduce the natural tooth. When this becomes a loose fit, the metal crown 15 that is an exact duplicate of the porcelain crown is used in the same manner as the others but the trimming is done with more care and we stop as soon as the metal crown will go to place. In this way the trimming of the 20 tooth can be done with great accuracy and since the porcelain crown is not tried on until the trimming is all done, there is little danger of breakage of this fragile porcelain.

But to give added protection to the porcelain crown, I propose to have them made 25 with an additional thickness around the neck end of the tooth. This extra thickness not only gives strength but is also often needed to provide a surplus of porcelain at this 30 point so it may be dressed away after the fitting is completed, to come flush with the circumference-surface of the natural tooth, which is of such a variety of irregular curves that unless there was a surplus all around 35 the porcelain crown, there might be insufficient porcelain to make a good flush finish. This extra thickness is shown as C C Figs. 3 and 4.

In cementing a porcelain jacket crown to 40 place on a prepared tooth, there is danger of either not getting the crown to go all the way to place because the cement doesn't have a way of escape and packs in the bottom of the socket; or there is danger of breaking the 45 porcelain crown because of the pressure necessary to press the surplus cement out of the socket when a close fit is procured.

To overcome these two difficulties, I propose to have the crowns made with one or 50 more small grooves running from near the bottom of the socket to the outer edge as shown in Figs. 6 and 7.

These grooves need not be deep to provide 55 gateway for the surplus cement to escape, thus allowing the crown to go to place with very little pressure.

I am aware that porcelain crowns have 60 been in use for many years whereby injured teeth have been restored to usefulness, but in the past, none have had the groove or gateway to allow the escape of the surplus cement, neither have they been made with a surplus of porcelain at the neck end as I have described to give strength and allow fitting. 65 Also, in the past such porcelain jacket crowns

were made to fit a tooth that had first been trimmed or prepared, while, I reverse the procedure by trimming the tooth to fit a crown that is already made up.

In the past the tooth was prepared in suitable shape for such a crown. A thin platinum matrix was then made to fit this prepared tooth. Over this matrix, a crown was built up and carved to look something like the tooth should. This required great skill 70 and much time and because the shape changed in the baking, it was not an easy matter to get the shape and size right. Then too, the color or shade was very difficult to get right 75 as it too changed in the baking. 80

Because of the great skill required and the time consumed, there are only a very few dentists using the porcelain jacket crown, first, because the fee for making one as now 85 done, must necessarily be too high for the general public to feel they can afford it, second, because the skill required is more than the average dentist has developed.

Since with my procedure and improved 90 crowns all made, most of the exacting skill is dispensed with as all that is necessary is a good eye to know a good match when it is placed side by side and the mechanical skill sufficient to trim the tooth to fit. All this 95 the dentist, if he is allowed to practice dentistry, should do with ease.

Thus placing this most desirable of all 100 restorations in the hands of all dentists where the general public can be served at prices within their reach, prices being reduced by the reduction in the time necessary to make the restoration and because it requires no special training and but little extra equipment.

Having thus described my invention, what 105 I claim and what I desire to secure by Letters Patent is:

1. The process of reducing a natural tooth enough and in such manner, that it will enter and approximately fit the socket of a porcelain crown, using for measuring and marking the tooth, while it is being reduced, duplicates as to size and form of the exterior of the crown, while the sockets graduate from a 110 duplicate to one or more sizes larger which 115 comprises reducing the tooth to fit large oversize sockets, then reducing the tooth to successively fit the intermediate oversize sockets, and then reducing the tooth to fit a duplicate socket of the porcelain crown.

2. The method of making metal duplicates and semi-duplicates of porcelain jacket crowns, which comprises embedding the crown in investment to form the mold for the outer surface of the crown and removing the crown and inserting a metal socket-former, having the desired relative size to complete the mold, whereby a metal duplicate or semi-duplicate of the porcelain crown may be 125 made.

3. A metal model of a natural tooth after it has been prepared to receive a porcelain crown, said model extending from a base, said base having a groove or gateway running from near the junction of the model and the base, to the bottom of the base, said gateway being provided with a gate to be used when desired.
4. A metal model of a natural tooth after it has been prepared to receive a porcelain jacket crown, extending from a base, said base having a removable handle extending from its bottom and said base having a gateway running from near the junction of the model and the base to the bottom of the base and said gateway being provided with a gate.
5. A metal model of a natural tooth after it has been prepared to receive a porcelain jacket crown, said model extending from a base said base having a gateway running from near the junction of the model and the base to the bottom of the base and said base having a ridge extending across the edge thereof.
- 25 6. A metal model of a natural tooth after it has been prepared to receive a porcelain jacket crown, said model extending from a base, said base having a ridge extending across its edge and a removable handle extending from its bottom and a gateway or groove running from near the junction of the model and the base to the bottom of the base, said gateway being provided with a gate to be used when desired.
- 35 7. The method of reducing and reshaping a natural tooth to a form generally accepted as the best shape to receive a porcelain jacket crown, by means of markers of suitable metal, having sockets formed in duplicate and semi-duplicates of the porcelain crown to be used, which comprises first, roughly reducing the natural tooth to size and form that will allow the metal semi-duplicate with the largest socket to be forced thereon, whereby it will mark the tight places; the tooth being then reduced at these points to allow the semi-duplicate with the next smaller socket to be forced thereon to mark where the tooth should be further reduced, and in like manner the tooth is further reduced, using markers with successively smaller sockets until the one that is a duplicate of the crown can be used to make the final marks for the finished reduction to make a good fit of the porcelain crown.
- 55 55. In testimony whereof, I have signed my name to this specification.

LEON LEROY POSTON.
